MATERIAL DISTRIBUTING MACHINE

Fred J. Faulkner, Brooklyn, N. Y.

Application August 19, 1938, Serial No. 225,831

4 Claims.

(Cl. 275-2)

This invention appertains to new and useful improvements in machines for distributing material, such as insecticidal dust, fertilizer and various other substances.

The principal object of the present invention is to provide a machine for distributing material of the character stated and which in use will confine the material to a definite surface area.

Another important object of the invention is to provide a machine for distributing material, such as insecticides, fertilizer and the like, which in operation will economize on the materials being used in that, any dust that will not settle quickly will be taken back into the distribution line.

Still another important object of the invention is to provide a machine which will be of simple construction yet efficient and constructed with the end in view of economizing as much as possible on the materials being employed so that there will be no waste.

These and various other important objects and advantages of the invention will become apparent to the reader of the following specification.

In the drawings:

Figure 1 represents a top plan view.

Figure 2 is a side elevation with a portion broken away and the fan damper removed.

Figure 3 is a sectional view taken substantially on the line 3-3 of Figure 1.

Figure 4 is an irregular longitudinal vertical sectional view taken substantially on the line 4-4 of Figure 1.

Figure 5 is a fragmentary vertical sectional view through the fertilizer distributing spout.

Figure 6 is a fragmentary vertical sectional view through the suction spout.

Figure 7 is a sectional view taken substantially on the line 7-7 of Figure 1.

Figure 8 is a sectional view taken substantially on the line 8-8 of Figure 2 with the damper in place.

Referring to the drawings wherein like numerals designate like parts, it can be seen that the machine includes a pair of angle beams 5-5 from the rear portions of which rises a pair of angle members 6-6. One flange of each of these angle members 6-6 of each beam 5 is formed with vertically spaced openings for accommodating horizontal pins 7. This forms adjusting means for an axle bar 8 whereby the frame 5-5 can be lowered or raised as desired. Wheels 20 are provided on the ends of the axle bar 8.

The frame beams 5-5 are connected by a

platform 9 upon which an internal combustion engine 10 is mounted.

At the forward end of the frame is a yoke 11 having a stub-shaft disposed upwardly into a vertically adjustable bearing 12. Side brace members 14 extend from a split sleeve 13 to connect to the forward portion of the platform 9, while rearwardly extending brace members 15 extend from the split sleeve 13 and connect to the platform 9. The bearing 12 extends upwardly through the split sleeve 13. The vertical edge portions of the sleeve are flanged and these flanges are connected by bolts and nuts 13a. These can be loosened to permit vertical adjustment of sleeve 13 therein to permit raising or lowering of the forward end of the machine to the correct position with respect to the adjusted position of the rear end of the machine, so that the platform will be uniformly spaced from the ground at both ends. Extending forwardly from the yoke 11 are arms 16 between which a tongue 18 is pivoted as at 17. A wheel 19 is mounted in the yoke 11 as shown in Figures 1 and 4.

Numerical 21 represents a hopper having an agitator 22 mounted in the bottom portion thereof and this has a shaft extending outwardly beyond one end of the hopper 21 to be equipped with a pulley 23.

The hopper 21 is provided with a closure 24 hingedly connected to the top thereof and also with a slide valve member 25 which extends upwardly and has a laterally disposed handle portion 26.

A spout 27 extends downwardly from a suction blower fan housing 28 and flares laterally at its lower end to form a distributor mouth 27a as clearly shown in Figure 5, and the point at which the spout 27 merges with the mouth 27a is provided with a plurality of baffles or distributing deflectors 29 therein. The lower portion of the hopper 21 fits into the intermediate portion of the spout 27 as at the point 30 and at this point the rear side of the hopper 21 at the lower portion thereof is formed with an opening 31 and over this opening can be partly or fully disposed the valve plate 25. Numerical 32 represents a deflector which is a portion of the rear wall of the hopper constructed to form the opening 31 and also a deflector permitting fertilizer to fall from the hopper before it is caught by the downrush of air.

Numerical 33 represents a suction spout which extends upwardly from a downwardly tapering mouth structure 34, this spout 33 connects to an extension 43 of the suction blower fan housing

28 in which a fan 35 is carried by a shaft 36. This shaft 36 extends through one end of the housing 28 and has a pulley 36a mounted thereon. A drive belt 37 extends from the pulley 36a over a pulley 38 on an engine shaft 39, this shaft 39 also having a pulley 40 between which and the pulley 23 a belt 41 is trained. The chute 27, housing 28 and spout 33 define a passageway in which air and material is blown to and sucked from the hood structure which is described hereinafter.

Reference character 41a represents a pipe connection between the engine exhaust and the spout 27 at a point below the hopper 21 for thoroughly heating the fertilizer before it is distributed at the mouth 27a.

Numeral 42 denotes the usual fuel tank for the engine.

The tubular extension 43 on the fan housing 28 is provided with a damper structure 44 at its outer end so that air to the fan 35 can be regulated.

It can now be seen, that when the engine 10 is in operation, the suction-blower fan 35 is operated as is the agitator 22. Fertilizer falls from the hopper 21 in a volume regulated by the valve plate 25 into the chute 27 where it is caught by air from the fan and driven downwardly through the mouth 27a to the ground 45. A flexible hood structure 46 extends downwardly from the frame and bottom of the platform 9 to ride against the ground and this forms an enclosure so that any buoyant parts of the fertilizer are kept within a restricted area. This buoyant material is caught by the suction through the mouth 34 and drawn upwardly and this laden air is used over again with as much additional fertilizer as is required.

It can further be seen that with the forward wall 46 and the rear wall 46 both constructed of sheet rubber or like material taken with canvas sides 46a, a shed-like structure is devised which will form a bottomless structure which will confine the discharged material over a limited area of the ground surface.

It will also be seen that as the suction-blower 35 operates, the pulverized material from the hopper 21 will be discharged from the mouth 27a evenly over the ground. There will obviously be a rise of very fine material from this lay and instead of this being lost, all this very fine material which will not stay in contact with the ground surface, or whatever surface the application is made to, will be taken up by the suction line 33 and put back into the distribution line 27 by the suction-blower device 35.

Normally the damper 44 will not be employed as there will be circulation from the distributing line 27 and mouth 27a, against the ground 45 and under the platform 9, back through the suction line 33 and device 35 to the distributing line 27. Thus the air under the platform and within the confines of the walls 46—46 and 46a—46a permeated with the very fine dust particles will be used over, thus eliminating any loss of material from the path of the ground surface being treated.

It will also be observed that damper 48 is a pivotal rectangular shaped plate operated by a suitable external control member. In other words, when the damper 48 is moved to closed position, the suction-blower 35 will be drawing vacuum and thus no effect will be had on the contents of the hopper 21 at the opening 31.

In some instances where certain materials are being used, especially materials of a very light nature and where for instance, a light film is to be placed on the surface to be treated, the suction line 34 is not employed. On this occasion, the damper 48 is closed and the damper 44 opened to the desired degree. Thus there is no disturbance of the film laid down by the discharged material through the mouth 27a.

10 While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A material distributing machine comprising a wheeled frame structure, a shed-like structure depending from the frame structure and having flexible end and side walls, said shed-like structure being open at its bottom, a material containing hopper supported on the frame and having a discharge passageway extending therefrom and into the shed-like structure adjacent the forward end thereof, and a suction line extending from the shed-like structure adjacent the rear end thereof, and a suction blower device interposed between the suction line and the passageway adapted to suck buoyant particles from within the shed-like structure and to deposit the same in the said passageway from the hopper.

2. A material distributing machine comprising a wheeled frame structure, a shed-like structure depending from the frame structure and having flexible end and side walls, said shed-like structure being open at its bottom, a material containing hopper supported on the frame and having a discharge passageway extending therefrom and into the shed-like structure adjacent the forward end thereof, and a suction line extending from the shed-like structure adjacent the rear end thereof, and a suction blower device interposed between the suction line and the passageway adapted to suck buoyant particles from within the shed-like structure and to deposit the same in the said passageway from the hopper, a regulatable air inlet for the suction-blower device, and a damper in the suction line.

3. A material distributing machine comprising a shed-like structure, means for moving the shed-like structure over the ground, and means for circulating buoyant particle laden air through said shed, said last-mentioned means consisting of a passageway having ends in open communication with the interior of the shed-like structure and suction blower means in the passageway.

4. A material distributing machine comprising a shed-like structure, means for moving the shed-like structure over the ground, and means for circulating buoyant particle laden air through said shed, said last-mentioned means consisting of a passageway having ends in open communication with the interior of the shed-like structure, suction blower means in the passageway, a material supply hopper opening into the passageway, and means for regulating the supply of material from the hopper to the passageway.

FRED J. FAULKNER.
